UNITED STATES PATENT OFFICE.

CHARLES R. GREUTER, OF SAUGUS, MASSACHUSETTS.

CARBURETER.

1,113,551.

Specification of Letters Patent.

Patented Oct. 13, 1914.

Application filed April 30, 1912. Serial No. 694,141.

To all whom it may concern:

Be it known that I, CHARLES R. GREUTER, a citizen of the United States, residing at Saugus, in the county of Suffolk and State 5 of Massachusetts, have invented certain new and useful Improvements in Carbureters, of which the following is a specification.

The present invention relates to certain new and useful improvements in the construction of carbureters such as are commonly employed for mixing and supplying explosive charges to internal combustion engines and the like.

The object of the invention is to provide a carbureter which is formed with a plurality of carbureting units and which embodies novel features of construction whereby the various carbureting units are brought successively into action as the engine is started, 20 and the suction produced thereby increased, and also novel means for regulating the mixture whereby the initial mixture for starting the engine is the richest, the mixture gradually becoming thinner until the 25 thinnest mixture is supplied when the engine has reached its full capacity.

A further object of the invention is to provide a carbureter which is durable and practical in its construction, which is always 30 under the complete control of the operator, and which operates in a positive and reliable manner to automatically regulate the volume and richness of the mixture according to the requirements of the engine when the 35 throttle is fully open.

With these and other objects in view, the invention consists in certain novel combinations and arrangements of parts as will more 40 fully appear as the description proceeds, the novel features thereof being pointed out in the appended claims.

For a full understanding of the invention, reference is to be had to the following description and accompanying drawings, in 45 which:—

Figure 1 is a side elevation of a carbureter constructed in accordance with the invention. Fig. 2 is a vertical sectional view showing two of the carbureting units 50 in section. Fig. 3 is a vertical sectional view taken at substantially right angles to the section line of Fig. 2 and showing one of the carbureting units in section and another of the carbureting units in side eleva-

tion. Fig. 4 is a horizontal sectional view 55 on the line 4—4 of Fig. 1. Fig. 5 is a horizontal sectional view on the line 5—5 of Fig. 2. Fig. 6 is a horizontal sectional view on the line 6—6 of Fig. 1. Fig. 7 is a detail view of the cam mechanism for controlling 60 the valve members at the discharge end of certain of the carbureting units. Fig. 8 is a perspective view of the upper end of the carbureter with the top plate or cap removed, and Fig. 9 is a perspective view of 65 the fuel nozzle and the manifold carrying the same.

Corresponding and like parts are referred to in the following description and indicated in all the views of the drawings by 70 the same reference characters.

Specifically describing the present embodiment of the invention, the numeral 1 designates a main casing within which a plurality of carbureting units is mounted, 75 the said units being preferably of the Venturi type. These carbureting units comprise the mixing or carbureting tubes 2, 3 and 4 which are contracted at intermediate points in their lengths and gradually flare out- 80 wardly toward their opposite ends. A water chamber 5 surrounds the various mixing tubes 2, 3 and 4, and warm water or any other suitable heating medium may be circulated through this chamber for the purpose of heating the carbureter. In the present instance suitable connections 6 and 7 are provided by means of which warm water from the engine jacket or any other suitable source may be circulated through the chamber 90 5.

The upper or discharge end of the various carbureting units open into a common chamber 8 which is formed by a removable cap plate 9 secured to the top of the casing 1. 95 This cap plate 9 is formed with the usual discharge or outlet opening 10 through which the explosive mixture passes on its way to the engine, the said outlet 10 being controlled by a throttle valve 11 which is 100 shown as of the butterfly type. This throttle valve is applied to a shaft 12 one end of which is provided with an arm 13 having a set screw 14 therein for engagement with a stop lug 15 to limit the closing movement of 105 the valve. A second arm 16 may also be provided, the said second arm being shown as integral with the arm 13 and arranged at

an angle thereto so as to engage the opposite side of the stop lug 15 when the throttle valve is in a full open position.

The carbureting or mixing tube 2 is always in open communication with the chamber 8, while the upper ends of the carbureting or mixing tubes 3 and 4 are controlled by the respective valves 17 and 18. These valves normally rest upon their respective seats by the action of gravity, although they are adapted to be lifted when the suction of the engine becomes sufficient for that purpose. The valve 18 is heavier than the valve 17 so that the valve 17 will lift and throw the second carbureting unit into operation before valve 18 lifts to throw the third carbureting unit into operation. The three carbureting units are thus brought successively into operation when the engine is started, thereby automatically increasing the volume of the mixture supplied to the engine as becomes necessary. The two valves 17 and 18 may be mounted in any suitable manner, although in the present instance they are shown as slidably mounted upon posts 19 projecting axially into the upper ends of the mixing or carbureting tubes from suitable cages 20, the said cages serving to limit the upward movement of the valves.

Means is also provided for positively holding the carbureter cut off valves 17 and 18 upon their seats when the main throttle 11 is closed, and successively releasing the said valve as the said throttle 11 is opened. For this purpose, the throttle shaft 12 is provided with a cam member 21 adapted to engage rollers 22 upon arms 23 and 24 which are rigid with shafts 25 and 26 journaled in opposite sides of the supporting casing. These shafts 25 and 26 are provided respectively with the valve engaging arms 27 and 28 which engage the respective valves 17 and 18 to hold the said valves upon their seats when the main throttle 11 is closed and the cam member 21 is swung downwardly into the position shown in Fig. 1. However, as the throttle 11 is opened, the cam 21 is moved so as to first release the arm 23 and thereby release the valve 17, and then to release the arm 24 and thereby the valve 18, both of the valves being released when the throttle is fully open and the cam 21 has the position shown in Fig. 7.

Fitted to the main casing at the lower ends of the carbureting or mixing tubes is a bottom plate 29 which is formed with the pockets 30 registering with the respective carbureting tubes. This bottom plate 29 is held yieldingly in position against the bottom of the casing 1 so as to normally form a tight joint therewith, although the plate is adapted to give and be forced temporarily away from the casing in the event back

pressure from the engine enters the carbureter. In the present instance this plate is shown as formed with openings receiving bolts 31 having coil springs 32 mounted thereon, the said coil springs bearing 70 against the plate and serving to hold the plate yieldingly in position. In this manner all danger of injury to the carbureter from back firing in the engine is avoided.

Fuel nozzles 33, 34 and 35 project upwardly into the respective carbureting or mixing tubes 2, 3 and 4, the said nozzles or jets being carried by a manifold 35 which is arranged under the casing. Suitable air inlet openings 36 are formed in the plate 80 29 and the fuel nozzles project through these openings. Air valves 37, 38 and 39 are slidably mounted upon the respective nozzles 33, 34 and 35 and normally drop by gravity to the lower limit of their movement where they close the respective air inlet openings 36. In practice, a very slight clearance space is preferably provided between the valves and the sides of the air inlet openings 36 so as to eliminate any 90 danger of rattling. These air valves 37, 38 and 39 are of different weights so as to be opened by varying amounts of suction. It will also be noted that the weights of the air inlet valves vary inversely as the 95 weights of the carbureter cut off valves at the upper ends of the mixing tubes. The air inlet valve 37 for the carbureter or mixing tube 2 which is always open at its upper end is heavier than the air inlet valve 38 for the carbureting or mixing tube 3, and this valve 38 is in turn heavier than the air inlet valve 39 of the carbureting or mixing tube 4. When the engine is first starting and the mixing tubes 3 and 4 are automatically cut off or closed by the valves 17 and 18, a rich mixture is furnished to the engine, owing to the fact that the air inlet valve 37 which regulates the supply of air to the mixing tube 2 is heavier than the remaining air inlet valves and admits a minimum amount of air. As the engine gradually produces more suction and lifts the cut off valve 17 from its seat so as to open the mixing tube 3 and throw the second carbureting unit into operation, a slightly thinner mixture is furnished to the engine, since the air inlet valve 38 for the mixing tube 3 is lighter than the air inlet valve 37 and admits a greater amount of air to the 105 mixing tube. It will further be obvious that when the engine reaches its full capacity and lifts the cut off valve 18 from its seat so as to throw the third carbureting unit into operation, the thinnest mixture will be 110 furnished to the engine, since the air inlet valve 39 for the mixing tube 4 is lighter than the air inlet valve 38 and will admit a still greater proportion of air for the same 115 amount of suction. A construction is thus 120

125 130

provided which automatically increases the volume of the charge and simultaneously decreases the richness thereof as the engine gradually reaches its greatest capacity.

5 A float feed chamber 40 is arranged in the main casing 1 and extends partially around the water chamber 5. This float feed chamber 40 communicates at one side thereof with a downwardly extending stand pipe 41 having the fuel feed pipe 42 in communication with the lower end thereof. This stand pipe 41 is also formed with lateral openings 43 which communicate with the manifold 35. A valve stem 44 extends loosely through 10 the pipe 41 and is provided at its lower end with a valve 45 adapted to engage a seat 46 to shut off communication between the fuel supply pipe 42 and the stand pipe 41, the valve seat 46 being located below the openings 43 so that the valve 45 does not interfere with the flow of fuel downwardly through the stand pipe 41 from the float feed chamber 40 to the manifold 35. A float 15 47 is arranged in the float chamber 40, the said float being pivoted upon a pin 48 and formed with arms 49 carrying pins 50 which engage a grooved collar 51 upon the valve stem 44. When the liquid fuel within the chamber 40 is exhausted and the float 47 drops to the position indicated by Fig. 2, the valve stem 44 is lifted so as to open the valve 45 and permit a fresh supply of fuel to pass upwardly through the stand pipe 41 into the chamber 40. As soon as the chamber 20 becomes sufficiently filled, the float is again lifted and automatically closes the valve 45. A spring 52 surrounds the upper end of the valve stem 44 and is interposed between the collar 51 and a cap 53 which is threaded upon a boss 54. This cap can be moved up and down to regulate the tension in the spring 52 and thereby regulate the operation of the float. This cap 53 is shown as having a polygonal base which is engaged 25 by a spring arm 54, the said spring arm serving to prevent accidental rotation of the cap. The manifold 35 is rigid with the main casing of the carbureter, the feed arm thereof being rigidly applied to the stand pipe 41, while a lug 55 at the opposite side thereof is engaged by a stem 56 projecting downwardly from the casing 1 and passing loosely through the yieldingly mounted bottom plate 29. It will be observed that with 30 this construction the nozzles do not take the hot fuel direct from the feed chamber 40, since the fuel must first pass through the stand pipe 41 which is arranged upon the exterior of the casing and completely exposed.

Having thus described the invention, what I claim as new and desire to secure by Letters Patent, is:—

1. A carbureter including a carbureting tube, means for supplying fuel to the tube,

means for controlling the outlet of the mixture from the tube, and a bottom closure for the tube comprising a yieldingly mounted cap plate having an air supply opening and constituting a back-pressure relief valve. 70

2. A multiple carbureter including a casting having a plurality of Venturi tubes, means for separately supplying fuel to the several tubes, means for separately controlling the outlet of the mixture from the several tubes, and a bottom closure for all of the tubes comprising a single yieldingly mounted cap plate having a plurality of air supply openings therein, respectively for the several tubes. 75

3. A carbureter including a series of carbureting units having differentially loaded suction controlled outlet valves, and differentially loaded suction controlled air inlet valves. 80

4. A carbureter including a series of carbureting units having differentially loaded suction controlled outlet valves, and differentially loaded suction controlled air inlet valves, said air inlet valves being loaded in inverse relation to said outlet valves. 85

5. A carbureter including a series of carbureting units, means for successively opening the outlets from said units as the suction from the engine increases, and differentially loaded valves controlling the air inlet openings of the carbureter units, said valves being inversely related to the means for bringing the carbureter units into action to provide for thinning out the mixture as the engine approaches its greatest capacity. 90

6. A carbureter including a plurality of carbureter units each of which is formed with an air inlet opening and a nozzle projecting through the air inlet opening, means for automatically bringing the carbureter units successively into action, and automatic air inlet controlling valves slidably mounted upon the nozzles, the said valves being normally closed and differentially loaded in inverse relation to the means for permitting the separate carbureter units to successively come into action. 95

7. A carbureter including a plurality of carbureter units, one of the carbureter units being always in communication with the engine, cut-off valves normally closing the other carbureter units and constructed to be successively opened as the suction from the engine increases, and valves controlling the air inlet openings of the carbureter units, said air inlet controlling valves being normally closed and being constructed to require varying degrees of pressure to open the same, that air inlet controlling 115 valve requiring the greatest amount of suction to open the same being associated with the carbureter unit which is always in communication with the engine, while the air inlet controlling valve requiring the least 120

amount of suction to open the same is associated with the carbureter unit which is last brought into action.

8. A carbureter including a plurality of carbureter units, one of the carbureter units being always open and ready for action, gravity actuated cut-off valves for the remaining carbureter units, said cut-off valves being of different weights so as to be successively lifted from their seats and opened as the suction from the engine increases, and gravity closed valves of different weights for the air inlets of the carbureter units, different amounts of suction being required to open the various air inlet controlling valves, and that air inlet controlling valve which requires the greatest suction to open the same being associated with the carbureter unit which is first brought into action, while the air inlet controlling valve requiring the least amount of suction to open the same is associated with the carbureter unit which is last brought into action.
25. 9. A carbureter including a carbureting tube, a plate yieldingly applied to one end of the tube and having the air inlet opening therein, a fuel nozzle projecting through the air inlet opening, and an air inlet controlling valve mounted upon the fuel nozzle so as to be normally closed and opened when a sufficient amount of suction is produced by the engine, the plate being adapted to give and release any back pressure from the engine.

10. A carbureter including a series of carbureter units, a throttle controlling the feed from all of the carbureter units to the engine, cut-off valves normally closing a portion of the carbureter units and constructed to be opened by the suction from the engine, positive means for holding the cut-off valves upon their seats when the throttle is closed, and air inlet controlling valves for the carbureter units, the said air inlet controlling valves being constructed to be opened by varying degrees of suction from the engine.

11. A carbureter including a series of carbureter units, a throttle controlling the supply of explosive mixture from all of the carbureter units to the engine, cut-off valves normally closing all of the carbureter units except one, the said cut-off valves being arranged to be successively opened as the suction from the engine increases, positive means for holding the cut-off valves

upon their seats when the throttle is closed and successively releasing them as the throttle is opened, and air inlet controlling valves for the carbureter units, the said air inlet controlling valves being normally closed and being constructed to require varying degrees of suction to open the same, that air inlet controlling valve requiring the most suction to open the same being associated with the carbureter unit which is always open, while the air inlet valve requiring the least suction to open the same is associated with the carbureter unit which is last brought into action.

12. A carbureter including a plurality of carbureter units, gravity closed cut-off valves applied to the discharge ends of certain of the carbureter units, the said gravity closed cut-off valves being all of different weights so as to be successively lifted as the suction from the engine increases, and gravity closed valves controlling the air inlets to the carbureter units, the said gravity closed air inlet controlling valves being also of different weights and being arranged inversely with respect to the gravity closed cut-off valves, so that those carbureter units which are first brought into action have heavier air inlet controlling valves and supply a richer mixture than the carbureting unit which is brought last into action and which has the lightest air inlet controlling valve and supplies the thinnest mixture.

13. A carbureter including a casing formed with a feed chamber, a plurality of carbureting tubes arranged within the casing, a plate yieldingly mounted upon the bottom of the casing and formed with air inlet openings for the carbureting tubes, a plurality of nozzles projecting through the air inlet openings, the said plate being adapted to yield and release any back pressure from the engine, a manifold carrying the nozzles, a feed pipe extending downwardly from the feed chamber on the exterior of the casing and communicating with the manifold, a fuel supply pipe leading to the feed pipe, and float controlled valve means automatically controlling communication between the fuel supply pipe and the feed pipe.

Signed at New York, in the county of New York and State of New York, this 29th day of April, A. D. 1912.
